UNITED STATES PATENT OFFICE.

ROLLAND T. R. HASTINGS, OF HIGHLAND PARK, ILLINOIS.

HAND BRUSH.

Application filed March 15, 1927. Serial No. 175,607.

This invention relates to hand brushes for toilet uses.

One object of my invention is to provide the cast metal back with means, such as upright flanges along the opposite sides of the back, for reinforcing or strengthening the back against distortion by the expansive force of the bristles in their sockets when wet, and thus prevent the formation of a hollow in the middle of the back for the collection of water to prevent quick drying of the bristles, as with brushes as heretofore made.

Another object of my invention is to provide the metal back with openings extending therethrough along the sides of the back exterior of the bristles for draining water off the upper surface of the back or quick drying of the bristles.

Other and further objects of my invention will appear from the following specification taken in connection with the accompanying drawings, in which—

Fig. 1 is a top plan view of my improved hand brush;

Fig. 2 is a side view of the same;

Fig. 3 is an enlarged vertical sectional view taken on line 3—3 of Fig. 1; and

Fig. 4 is a fragmentary vertical sectional view on line 4—4 of Fig. 3.

As shown in the drawings, my improved hand brush has a back 1, preferably die-cast from white or like metal and given generally rectangular form. Said back 1 is provided in its under side with a plurality of sockets or cavities 2, 2 to receive the folded upper ends of tufts of bristles 3, 3. The sockets or cavities 2, 2 are preferably arranged in a plurality of substantially parallel rows extending lengthwise of the back.

The back 1 has holes or apertures 4, 4 opening into the sockets from the upper side of the back, so that loops 5, 5 of a wire 6 may extend into the sockets and engage under the folds in the bristles for holding the same tightly in the sockets, as shown in Figs. 3 and 4. The wire 6 lies in grooves 7, 7 in the upper surface of the back 1 over and following the rows of sockets, as shown.

The folded upper ends of the tufts of bristles 3, 3 substantially fill the sockets or cavities 2, 2, so that the bristles may be held tightly in the sockets and thus not loosen and fall out in the use of the brush.

When wet, the folded upper ends of the bristles expand and in cast metal backs as

heretofore designed, the backs have been distorted downward in their midportions, forming hollows for water to collect and prevent quick drying of the bristles.

To overcome this objection, I cast upright flanges 8, 8 along the opposite sides of the back 1, as shown in the drawings. These flanges 8, 8 project above the upper surface of the back and extend substantially the full length thereof and reinforce or strengthen the back against distortion when the folded upper ends of the bristles expand in their sockets 2, 2 when wet. The side portions 9, 9 of the back between the outermost side rows of bristles 3 and the flanges 8 are inclined downward from the flanges, and each is provided with a row of holes or openings 10, 10 extending therethrough exterior of the bristles for draining water off the upper surface of the back 1 for quick drying of the bristles. The back 1 over the bristles is in effect solid for the holes 4 are closed by the wire loops 5 and would not allow the channel formed by the back 1 and flanges 8 to drain if it were not for the provision of the holes 10. These are an important feature of my invention because they prevent water collecting on the back to hinder drying of the bristles.

The upright flanges 8, 8 form hand grasping portions at the sides of the back so that the brush may be readily picked up and handled while in use. To prevent slipping of the fingers off these flanges 8, they are corrugated along the outer side surfaces by means of a plurality of grooves 11, 11, as shown in Figs. 2 and 3.

The details of structure shown and described may be variously changed and modified without departing from the spirit and scope of my invention.

I claim as my invention:

1. A hand brush having a cast metal back having a relatively thin flat body provided with a plurality of sockets in its under side, bristles substantially filling said sockets, means holding the bristles therein, and upright flanges cast on the body along the opposite sides thereof and extending above the same, said flanges providing hand grasping portions for the body and also strengthening the body against distortion by the expansive force of the bristles in the sockets when wet.

2. A hand brush having a cast metal back having a relatively thin flat body provided with a plurality of sockets in its under side,

bristles substantially filling said sockets, means holding the bristles therein, and upright flanges cast on the body along the opposite sides thereof and extending above the same, said flanges forming with the body an upwardly opening channel, said back having a plurality of openings extending therethrough for draining said channel.

3. A hand brush having a cast metal back 10 with a plurality of sockets in its under side bristles substantially filling said sockets, and means holding the bristles therein, said back having its side portions extending beyond the bristles and extending upward to provide 15 with the back an upwardly opening channel, said back having a plurality of drain openings in its side portions exterior of the bristles.

4. A hand brush having a cast metal back 20 with a plurality of sockets in its under side, bristles substantially filling said sockets, means holding the bristles therein, and upright flanges cast on the back along the opposite sides thereof, said flanges providing

grasping portions for the back and being 25 corrugated along their outer sides.

5. A hand brush having a cast metal back with a plurality of sockets in its under side, bristles substantially filling said sockets, and means holding the bristles therein, said back 30 having its side portions inclined upward and terminating in upright flanges, said inclined portions having a plurality of drain openings extending therethrough exterior of said bristles. 35

6. A hand brush having a cast metal back with a plurality of sockets in its under side, folded tufts of bristles having their folded ends inserted in and substantially filling said sockets, wire loops engaging the folded 40 portions of said bristles holding the same in said sockets, and upright flanges cast on the back along its opposite sides, said back having drain openings extending therethrough inside of and along said flanges. 45

In testimony whereof I affix my signature this 9th day of March, 1927.

ROLLAND T. R. HASTINGS.
